UNITED STATES PATENT OFFICE

104,649

DESIGN FOR A CONTAINER OR SIMILAR ARTICLE

Louise Love Black, Chicago, Ill.

Application September 8, 1934, Serial No. 53,235

Term of patent 14 years

To all whom it may concern:

Be it known that I, Louise Love Black, a citizen of the United States, residing at Chicago, in the county of Cook and State of Illinois, have invented a new, original, and ornamental Design for a Container or Similar Article, of which the following is a specification, reference being had to the accompanying drawing, forming a part thereof.

In the drawing,

The figure is a perspective view of a container or similar article showing my new design. The shading is indicative of mirrors.

I claim:

The ornamental design for a container or similar article, as shown and described.

LOUISE LOVE BLACK.
